(57) **CLAIM**

The ornamental design for a rear fender for an armored vehicle, as shown and described.

DESCRIPTION

FIG. 1 is front perspective view of a rear fender for an armored vehicle of my new design;

FIG. 2 is a right side view thereof;

FIG. 3 is a front view thereof;

FIG. 4 is a rear view thereof; and,

FIG. 5 is a top plan view thereof.

The inside of the fender of my design forms no part of the claimed design. My design includes a mirror image of the embodiment depicted.
